Patented Mar. 29, 1960

187,527

MITTEN GUARD

Sally Greene, Cranston, R.I.

Application November 19, 1957, Serial No. 48,541

Term of patent 3½ years

(Cl. D17—3)

FIG. 1

FIG. 2

Fig. 1 is a top plan view of a mitten guard showing by new design.

Fig. 2 is a side elevational view thereof; and

Fig. 3 is an enlarged perspective view of one of the jaws shown in Fig. 1 as it appears in open position.

I claim:

The ornamental design for a mitten guard, as shown.
